[57] CLAIM

The ornamental design for a tire, as shown and described.

DESCRIPTION

FIG. 1 is a perspective view of a tire showing our new design it being understood that the tread pattern is repeated uniformly throughout the circumference of the tire, the opposite side being the same as that shown; FIG. 2 is a front elevational view thereof; FIG. 3 is a side elevation view thereof; and, FIG. 4 is an enlarged, fragmentary plan view of a portion of the tire of FIG. 1.
